UNITED STATES PATENT OFFICE.

LLOYD J. HIBBARD, OF WILKINSBURG, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed January 5, 1921. Serial No. 435,102.

To all whom it may concern:

Be it known that I, LLOYD J. HIBBARD, a citizen of the United States, and a resident of Wilkinsburg, in the county of Allegheny 5 and State of Pennsylvania, have invented a new and useful Improvement in Motor-Control Systems, of which the following is a specification.

My invention relates to motor-control systems and it has particular relation to control systems for operating electric locomotives.

The object of my invention is to provide a motor-control system for governing an 15 electric locomotive, whereby the number of contactors will be greatly reduced although securing effective and desirable starting and accelerating characteristics for the locomotive.

20 In order to obtain desirable starting characteristics, the initial steps must be so graduated as to take out the "slack" in the train smoothly. In order to obtain desirable accelerating characteristics, the accelerating 25 steps must be so graduated as to give smooth notching and maintain the average value of accelerating tractive effort as near to the slipping-point of the wheels as is practicable.

30 It is desirable to maintain the accelerating tractive effort as near this point as possible, thereby more quickly bringing the locomotive to full speed and lessening the time in which resistors are required in circuit 35 with the secondary windings of the locomotive. This action becomes necessary, since the energy consumed by the resistors is lost and, furthermore, if the resistors are subjected to a heavy current for a considerable 40 period of time, they tend to become heated to a dangerously high value.

Heretofore, the propelling motors of an electric locomotive have been operated simultaneously during the starting and accelerating periods, but, in my invention, the motors are either operated singly, successively, or in pairs, successively, thereby reducing the number of contactors required to start and accelerate the locomotive and 45 train for any predetermined number of starting and accelerating steps.

For a better understanding of my invention, reference should be made to the accompanying drawings—

Figure 1 of which is a diagrammatic view, 55 in side elevation, of an electric locomotive;

Fig. 2 is a diagrammatic view of a master controller employed to govern the operation of the locomotive shown in Fig. 1;

Fig. 3 is a schematic view of a plurality 60 of motors which operate the locomotive shown in Fig. 1, and which are governed by the master controller shown in Fig. 2.

Fig. 4 is a chart, of well-known form, showing the sequence of operation of the 65 contactors and circuit-breakers that are employed to operate the motors shown in Fig. 3; and

Fig. 5 is a curve chart indicating the manner in which the motors are accelerated. 70

Referring to Fig. 1, a locomotive 1 is mounted upon driving trucks 2 and 3 and bogie trucks 4 and 5. The driving wheels 6 of each main truck are mechanically connected in groups by suitable rods 7. A plurality of propelling motors 8 and 9 are mechanically connected to the driving wheels 6 of the front truck 2 by suitable gear-wheels 11 and driving rods 12, and motors 13 and 14 are similarly connected to the 80 driving wheels 6 of the rear truck 3.

Referring to Fig. 3, each of the motors 8, 9, 13 and 14 is provided with a primary-phase winding 15 and a secondary-phase winding 16. The primary windings 15 of 85 the motors 8, 9, 13 and 14 may be energized from a source of electrical energy (not shown) through suitable supply conductors 17, when a plurality of three-phase circuit-breakers 18, 19, 20 and 21 are closed, respectively.

A plurality of sets of resistors 22 are respectively connected in circuit with the secondary windings 16 of the motors 8, 9, 13 and 14. A plurality of contactors 23 to 38, 95 inclusive, are employed to accelerate the motors 8, 9, 13 and 14, by shunting portions of the starting resistors 22. It is to be understood that more contactors may be employed to shunt different portions of the starting 100 resistors 22, if it is considered necessary. For the sake of simplicity, a minimum num-

ber of contactors are shown; but they are sufficient in number to fully illustrate my invention.

In Fig. 2, a master controller 39 is provided with a contact segment 40 of suitable contour for engaging a plurality of contact fingers 41 in the desired sequence. The master controller 39 is provided with a starting position and with a plurality of operating positions, *a* to *p*, inclusive.

The operation of the motor 8 is begun by actuating the master controller 39 through the starting position to position *a*, thereby establishing a circuit from a suitable source of energy, such, for example, as a battery 42, through contact fingers 41 and contact segment 40 of the master controller 39 and the actuating coil of the circuit-breaker 18. The motor 8 will tend to operate at its lowest speed since the corresponding resistors 22 are entirely in circuit with its secondary phase winding 16.

The master controller 39 is next actuated to its second, *b*, third, *c* and fourth, *d*, positions successively, thereby energizing the actuating coils of the three-phase circuit-breakers 19, 20 and 21, causing them to close.

The wheels of the locomotive 1 will begin to rotate as soon as the motor 8 is energized, and the locomotive will start pulling a few cars that are nearest it, in a forward direction. When the engineer believes that the increasing load is such that the locomotive is about to stop, he actuates the master controller forward another notch. He must repeat this action each time that it becomes apparent that the power of the motor is not sufficient to draw the next few stationary cars in a forward direction.

If the engineer should accelerate the locomotive too rapidly, there is danger that the draw-bars of some of the cars will be impaired; therefore, the desirable tractive effort per notch for a locomotive is necessarily limited by the character of the rolling stock it is to haul and by the number of cars in the train.

After all the slack has been removed from the train, corresponding to the occupation of position *l*, for example, of the master controller, the locomotive and cars may be accelerated to full speed. Generally, the tractive effort per truck that can be maintained without exceeding the slipping-point of the wheels is the limiting factor by the time all of the slack has been taken up. Hence, it becomes desirable to distribute the load per notch upon the driving wheels of both the forward and the rear trucks.

After the slack has been removed from the train, or the tractive effort per truck approximates the slipping-point of the wheels, the acceleration of the motors 8, 9, 13 and 14 is accomplished by actuating the master

controller through positions *m* to *p*, inclusive. When the master controller 39 is actuated from position *l* to position *m*, accelerating contactors 31 and 35 are closed, in accordance with the sequence chart shown in Fig. 4, thereby shunting portions of the corresponding resistors 22 which are in circuit with the secondary windings 16 of each of the motors 8 and 13.

When the master controller 39 is actuated from position *m* to position *n*, contactors 32 and 36 close, thereby shunting the remaining portions of the resistors 22 which are in circuit with the secondary windings 16 of the motors 8 and 13, thus bringing the phase windings of the individual motors in balanced relation to each other.

The motors 9 and 14 are next accelerated by the master controller 39 being actuated to position *o*, thereby closing contactors 33 and 37 and thus shunting portions of the resistors 22 which are in circuit with the motors 9 and 14, respectively. When the master controller 39 is actuated to position *p*, contactors 34 and 38 are closed to again accelerate the motors 9 and 14, respectively, and balance their secondary phases.

Approximately the same tractive effort of the locomotive per notch of the master controller may be secured during the acceleration of the train by closing the contactors 33 and 37 simultaneously, after closing contactors 31 and 35 and before closing contactors 32 and 36. However, this method of accelerating the motors would cause the load upon the phase windings to be unbalanced for a considerable longer period than by the method first set forth.

The graphs or curves shown in Fig. 5 show the approximate relation of the speed to the tractive effort of the motors of the locomotive per notch. Curves 43 show the relation of the speed to the tractive effort during the period the locomotive is taking the slack from the train (positions *a* to *l*, inclusive). Curves 44 show the relation of the speed to the tractive effort during the acceleration of the locomotive thereafter.

If the allowable variation per notch between the minimum desirable tractive effort, represented by the line 45, and the maximum allowable tractive effort, represented by the line 46, is equal to a 25% variation in the tractive effort of the locomotive per notch, a more desirable and effective acceleration may be obtained by maintaining the acceleration between smaller limits, as represented by a line 47 and the line 46. This condition gives 125% variation in tractive effort per notch, since the average accelerating tractive effort has been increased from line 47 to a line half way between lines 47 and 46, and the notching will be smoother.

It is evident that, by having all of the tractive effort increment per notch or posi-

tion of the master controller produced by one motor during all or part of the starting period and by a pair of motors during the accelerating period, the necessary number of contactors is reduced as compared with prior systems. To effect the same total increase in tractive effort by operating all motors simultaneously each notch, four times as many contactors would be required 10 and only one-fourth the effective variation in resistance in circuit with the secondary winding of each motor could be obtained per notch.

It would also be within the spirit of my 15 invention to accelerate the motors upon one truck successively before accelerating the motors of another truck. However, more satisfactory operation may be secured by alternately accelerating each set of driving 20 wheels.

While I have shown my invention in a preferred form, it is apparent that minor modifications may be made in the arrangement of apparatus and control circuits without departing from the spirit of the invention. I desire, therefore, to be limited only 25 by the scope of the appended claims.

I claim as my invention:

1. In a motor-control system, the combination with an electric locomotive having a plurality of driving wheels and a plurality of motors for actuating said driving wheels, each of said motors having a plurality of windings, of means for alternately accelerating said motors through a plurality of steps while maintaining the relation of said windings.

2. In a motor-control system, the combination with an electric locomotive having a plurality of driving wheels and a plurality of motors for actuating said driving wheels, each of said motors having a plurality of windings, of means for successively increasing the torque of said motors throughout 40 a number of steps while maintaining the relation of said windings, said increase in torque of each motor being substantially equal to the allowable accelerating rate of 45 said locomotive.

3. In a motor-control system, the combination with an electric locomotive having a plurality of driving wheels and a plurality of motors for actuating said driving wheels, each of said motors having a plurality of 50 windings having a predetermined number of poles, of means for successively increasing the torque of said motors while maintaining the number of said poles constant, said increase in torque of each motor corresponding to the maximum variation in 55 torque per notch during the starting period of said locomotive.

4. In a motor-control system, the combination with an electric locomotive having 60 a plurality of sets of driving wheels, means

for mechanically connecting the wheels of the sets together and a plurality of motors provided with primary and secondary windings for actuating said sets of wheels, of a master controller having a plurality of 70 positions for governing said motors, said controller being capable of accelerating said motors successively through a number of positions while maintaining the relation of said windings.

5. In a motor-control system, the combination with an electric locomotive having a plurality of trucks provided with driving wheels, means for mechanically connecting the driving wheels of each truck, and a 80 plurality of groups of motors for actuating said wheels, each of said motors having a plurality of windings, of a master controller having a plurality of positions for so governing said motors that the groups of wheels 85 of said truck are accelerated successively step by step while maintaining the relation of one winding to another.

6. In a motor control system, the combination with a locomotive having a plurality of wheels arranged in groups, a plurality of motors for actuating said wheels, each of said motors having a plurality of co-operating windings and a plurality of translating devices in circuit with one of 90 said windings, of means for varying the connections of said translating device successively, whereby a motor which actuates one group of wheels is repeatedly accelerated prior to the repeated acceleration of a 95 motor actuating another group of wheels.

7. In a motor-control system, the combination with a plurality of wheels arranged in groups, a plurality of motors for actuating said wheels, each of said motors having a primary and a secondary winding, and a resistor in circuit with each of 100 said secondary windings, of means for shunting said resistors successively to secure step-by-step acceleration of said motors, 105 whereby a plurality of motors which actuate different groups of wheels are alternately accelerated.

8. In a motor-control system, the combination with a plurality of wheels, means 110 for mechanically connecting said wheels, and a plurality of motors for actuating said means, each of said motors having a predetermined number of poles, of means for alternately accelerating said motors while 115 maintaining constant the number of poles of said motors.

9. In a motor-control system, the combination with a plurality of wheels, means for mechanically connecting said wheels, and a plurality of motors for actuating said wheels, each of said motors having a primary and a secondary winding, of a plurality of resistors in circuit with said secondary windings of said motors, a plurality 120 125 130

- of contactors for shunting said resistors, and a master controller for so governing said contactors that said motors are accelerated alternately.
- 5 10. In a motor-control system, the combination with a plurality of motors, of means for accelerating said motors successively during a portion of the starting period and afterwards accelerating certain of 10 said motors in pairs.
11. In a motor-control system, the combination with a plurality of motors, of means for first accelerating said motors successively in accordance with predetermined 15 conditions and second accelerating groups of said motors successively.
12. The combination with a locomotive having a plurality of wheels, said wheels being mechanically connected in groups, of a plurality of motors for actuating said wheels, and means for first accelerating said motors successively during a portion of the starting period and afterward accelerating said motors in groups.
- 20 13. The combination with an electric locomotive having a plurality of wheels mechanically connected in groups, of means comprising a plurality of motors and a plurality of current-varying devices for accelerating said groups of wheels alternately by operating said devices.
14. The combination with an electric locomotive having a plurality of wheels mechanically connected in groups, of means for alternately accelerating said groups of wheels and later accelerating said groups of wheels simultaneously.
- 25 15. The combination with an electric locomotive having a plurality of wheels, a plurality of motors for driving said wheels, means for mechanically connecting certain of said motors to said wheels, and means for first accelerating said motors alternately and afterward accelerating certain of said motors simultaneously.
- 30 16. The combination with a locomotive having a plurality of driving wheels mounted upon trucks, a plurality of motors arranged in pairs for actuating said driving wheels, means for mechanically connecting the driving wheels of each truck to the corresponding pair of motors, and means for accelerating said motors alternately and simultaneously.
- 35 17. The method of starting and accelerating a locomotive having a plurality of driving motors that comprises actuating said motors alternately and later accelerating groups of said motors simultaneously.
- 40 18. The method of starting and accelerating a locomotive having a plurality of driving wheels driven by said motors that comprises accelerating said motors successively until the maximum allowable tractive effort per wheel is secured and then accelerating said motors in groups to distribute approximately the same tractive effort upon a greater number of wheels.
- 45 19. The method of starting and accelerating a locomotive having a plurality of driving wheels mechanically connected in groups and a plurality of motors for actuating said groups that comprises accelerating said motors successively until the maximum allowable tractive effort per notch for a group of wheels has been secured and then accelerating said motors, in groups, thereby distributing the maximum allowable tractive effort per notch over a greater number of wheels.
- 50 20. In testimony whereof, I have hereunto subscribed my name this 19th day of December, 1920.
